SPACE CONDITION RESPONSIVE INSTRUMENT

Henry Dreyfuss, South Pasadena, Calif., assignor to Minneapolis-Honeywell Regulator Company, Minneapolis, Minn., a corporation of Delaware

Filed Sept. 25, 1959, Ser. No. 57,683

Term of patent 14 years

(Cl. D52—7)

Fig.1

Fig.2

Fig.3

Fig.4

Figure 1 is a front view of a space condition responsive instrument embodying my design; and

Figure 2 is a side view of the instrument shown in Figure 1 looking toward the right side of Figure 1; and

Figure 3 is a top view of the instrument shown in Figure 1; and

Figure 4 is a side elevation of the instrument opposite to that of Figure 2 showing the lower portion partially cutaway.

I claim:

The ornamental design for a space condition responsive instrument, substantially as shown.
